UNITED STATES PATENT OFFICE.

LUCIUS HOMER BROOKS, OF ATLANTA, GEORGIA.

RAZOR STROP.

Application filed March 3, 1927. Serial No. 172,379.

This invention aims to provide a razor strop of such length that it can be used conveniently with the human hand as a support, novel means being provided for connecting the strop to a finger of the hand.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in elevation, a device constructed in accordance with the invention, mounted on the hand of an operator;

Figure 2 is a longitudinal section;

Figure 3 is an end elevation;

Figure 4 is an elevation of the retainer; and

Figure 5 is an end view of the retainer.

The body 1 of the strop is flexible, and approximates the human hand in length. The body may be made of any desired materials: for instance, it may comprise strips 2 and 3 secured together back to back, one strip presenting a honing surface, and the other strip presenting a stropping surface. A U-shaped retainer 4, generally made of metal, receives one end of the body 1 and is provided at its

inner end with alternating spaced anchor elements, such as prongs, which enter the body 1 from opposite sides thereof. Attaching members 6 are provided and may be made of elastic material. They are flexible, in any event. The ends of the attaching members 6 pass between the arms of the retainer 4 and the body 1, the prongs 5 passing through the ends of the attaching members 6, to hold them in the looped form seen best in Figure 3. The retainer 4 has inwardly extended flanges 7 which pinch the body 1 closely. The end flanges 7 not only give a finish to the retainer 4, but, as well, they prevent the attaching members 6 from being frayed where its ends pass inwardly between the arms of the retainer 4 and the body 1 of the strop.

The operator can place either surface of the body 1 next to his hand, and strop or sharpen upon the opposite surface of the body, the article being reversible, since either of the loop-shaped attaching members 6 may be placed on one of the fingers of the hand.

What is claimed is:—

A razor strop comprising a body approximating the human hand in length, a loop-shaped attaching member disposed transversely of the body at one end thereof, and a U-shaped retainer receiving said end of the body and provided with prongs engaging the attaching member and the body to hold the attaching member upon the body, the opposite end of the body being free.

In testimony that I claim the foregoing as my own, I have hereto affixed my signature.

LUCIUS HOMER BROOKS.
